UNITED STATES PATENT OFFICE.

WILLIAM KAISLING, OF CHICAGO, ILLINOIS, ASSIGNOR TO MILO G. KELLOGG, OF CHICAGO,
ILLINOIS.

INTERRUPTER.

No. 874,511.

Specification of Letters Patent.

Patented Dec. 24, 1907.

Application filed January 3, 1907. Serial No. 350,575.

To all whom it may concern:

Be it known that I, WILLIAM KAISLING, a citizen of the United States, and resident of Chicago, county of Cook, and State of Illinois, have invented a certain new and useful improvement in Interrupters, of which the following is a specification.

The present invention relates to interrupters generally and more particularly to that class of interrupters which are intended for use with step-by-step mechanisms such as are commonly employed in the automatic switches for example the first and second selectors, of automatic telephone exchange systems. The general relations of the interrupter to the other parts of an automatic switch of such a system are set forth with considerable particularity in United States Patent No. 831,875, dated September 25, 1906.

20 The general object of the present invention is to improve upon interrupters of the prior art.

More specific objects are to provide such an arrangement of parts that positive and quick making and breaking of the circuit of the interrupter will invariably be accomplished during its operation, also to provide a device which will be durable and cheap to manufacture and which will have its parts so arranged that they will be readily accessible for the purpose of inspection or repair.

In carrying out my invention I preferably employ as the circuit breaking element of the interrupter an oscillating contact member associated with an actuating member carried by and movable with the armature and bearing upon the end of one or more of the oscillating members and provided with a cam face which co-operates in the making and breaking of the circuit produced by the movement of the contact member. The nature of the invention will be more fully understood upon reference to the following detailed description taken in connection with the accompanying drawing, and the scope of the invention will be more particularly pointed out in the appended claims.

In said drawing, Figure 1 is a top plan view of a portion of an interrupter constructed in accordance with the present invention; Fig. 2 is an end elevation of the complete interrupter; Fig. 3 a bottom plan view of the same; Figs. 4, 5 and 6 are views similar to Fig. 2, illustrating different operative positions of the parts; Figs. 7, 8, 9 and

10 are similar views of a modified form of the invention, also illustrating the parts in different operative positions; Fig. 11 is a diagram of circuits. Throughout these views, like characters refer to like parts.

Referring in detail to the drawing, 1 designates the electromagnet of the interrupter which preferably comprises a winding located upon a suitable core 2 and having one end connected to a terminal 3 and the other end to a terminal 4. The core 2 is provided with suitable pole-pieces 5 and 6 which extend transversely thereto and terminate in proximity to the armature 7 which is pivotally supported at one edge by the pivot pins 8 and 9 which extend through end plates 10 and 11 respectively, composed of brass or other suitable non-magnetic material. These plates 10 and 11 are secured to the pole-pieces 6 and 5 respectively by any suitable means. The terminals 3 and 12 located at one end of the magnet spool extend through and are suitably insulated from the plate 10, and the terminal 4 similarly extends through and is suitably insulated from the plate 11.

Preferably the interrupting elements and the associated parts are mounted upon the plate 11, as illustrated, in a position in which the various parts may be readily inspected or removed for the purpose of repair. The interrupting element comprises the oscillating member 13 carrying, near its free end, contact 14 which is insulated from the member 13 but electrically connected, by means of the flexible conductor 15, with the terminal 4 of the electromagnet. An adjustable contact 16, having the form of a screw, is threaded through the conducting post 17 and secured in place by a suitable lock-nut 18. The post in turn is passed through an opening in the plate 11 and is insulated therefrom. The lower end of the post is provided with a retaining nut 19 which firmly connects the post to the plate and maintains the terminal 20 in good electrical contact. The vibratory circuit of the interrupter extends from the terminal 3 through the winding of the electromagnet 1, terminal 4, flexible conductor 15, contacts 14—16, post 17 and terminal 20. In this case, the terminal 12 is idle but, if desired, the terminal 20 might be electrically connected to the terminal 12 and the latter is provided for this purpose. The oscillating contact arm 13 is pivotally supported at one end upon a bracket 21 secured

60

105

110

to the plate 11 by any suitable means, as by the screw 22. This bracket is provided with a projection 23 which forms a stop and limits the opening movement of the contact member 13. The contact member is moved to its extreme positions through the agency of an actuating member 24 which is pivotally secured at 25 to an irregularly shaped plate 26 of brass or other suitable non-magnetic material which is secured to the adjacent end, and forms a projection of the armature 7, by any suitable means as the screws 27. The actuating member 24 moves to and fro with the armature and is preferably sprung 15 pressed against the end of the member 13 which has its end recessed to form a guide for the said member 24. The spring pressure is brought about by the employment of a leaf-spring 28 which engages the under side 20 of the rearward projection 29 on the member 24 at one end and is firmly secured at its opposite end to a bracket 30 which is in turn secured to the plate 11 by a screw 31 and a pin 32. The actuating member 24 is provided with the cam face 33 which, in the present instance, comprises two oppositely directed inclined surfaces. This cam face cooperates with the adjacent end of the contact member 13 to cause positive action on 30 its part in maintaining and quickly breaking contact between the contacts 14 and 16. From an inspection of the drawing, it will be noted that the portion of the contact member 13 which engages the cam face 33 is oppositely inclined so as to form a sort of knife-edge which, together with the corresponding edge of the cam face 33, insures positive action at a definite point in the movement of the member 24. In addition to the interrupting mechanism heretofore described, the projecting plate 26, carried by the armature, also carries at its outer end a driving pawl 34 which is adapted to engage a suitable ratchet such as the ratchet-wheel 35. The pawl 34 is pivoted at 36 and its engaging end is pressed toward the ratchet 35 by means of a leaf-spring 37, bearing at one end upon the pawl and firmly secured at its opposite end to a projection 38 of the plate 26 by suitable means as the screws 39. The forward end of the pawl is beveled and cooperates with the beveled stop 40 in giving a single step to the ratchet 35 upon each attraction of the armature. The stop 40 is preferably secured 50 to the plate 11 by screws 41. The return movement of the pawl 34 and the armature 7 is limited by a stop 42 preferably formed by turning over an adjacent portion of the plate 11.

55 In Fig. 11, a simple diagram of circuits is represented to show the function of the interrupter, which is illustrated at 43, in its application to an automatic switch of the type previously referred to. In this circuit, 60 the interrupter contacts are diagrammat-

ically illustrated at 44 and 45 and the contacts, together with the winding of the interrupter, are included in circuit with a grounded source of current supply, such as the battery 46, and with the contacts 47—48 70 of a suitable control relay 49, the contact 48 being grounded. The control relay 49 may be, in the automatic switch above referred to, what is commonly called the private relay. From the diagram it will be seen that 75 when the relay 49 is energized, a circuit is completed through the interrupter and this circuit, although made and broken by the action of the interrupter, is otherwise maintained as long as the relay 49 is energized. 80 During this time, it will be seen that the armature of the interrupter will cause the ratchet 35 to advance step-by-step and this advance movement will be continued until the relay 49 is deenergized. In the diagram, 85 circuit through the relay 49 is adapted to be initially closed by the manual operation of a key 50 which is provided with the grounded contact 51. In the diagram, 52 represents the movable contact or wiper, commonly 90 called the private wiper, of the switch mechanism previously referred to, which is moved in response to the movements of the ratchet 35 over the associated bank contacts 53. These bank contacts are connected to 95 trunks 54 which, in the operation of associated switch mechanism represented by the relay 55, are adapted to be open-circuited or grounded in accordance with the condition of such mechanism. Thus if relay 55 is energized, its contact 56 will engage its grounded contact 57; and upon the first step of the wiper 52, the circuit of relay 49 will not be interrupted even though key 50 be open. Thus the vibratory circuit of the interrupter 100 will be continued and the wiper 52 advanced over the contacts 53 to the next position. This action will continue until the wiper 52 engages an ungrounded contact 58 in which event the circuit of relay 49 will be interrupted and said relay be deenergized with a consequent interruption of the circuit of the interrupter. 105

110 During the operation above outlined, the oscillating contact member 13 will be thrown from its engaging to its non-engaging position and vice versa, through the action of the armature 7 and the actuating member 24 carried thereby. Thus upon the attraction of the armature, the member 24 will be 115 moved downward and, by means of the lower inclined face of the cam 33, will force the contact member 13 downward, thus maintaining good contact between the contacts 14 and 16 until the so-called knife-edges of the cam 33 and contact member 13 just pass each other. 120 As soon as this takes place, the upper inclined surface of the cam 33 will, by reason of the pressure exerted upon the member 24 by the spring 28, positively and rapidly force 125

130

the contact member 13 upward into engagement with the stop 23.

In Fig. 4, the parts are shown with the knife-edges of the members 13 and 24 just about to pass. In other words, contact between contacts 14 and 16 is just about to be broken. As will be apparent from the position of the pawl 34 in this figure, this occurs at practically the end of the attracted or downward movement of the armature and its connecting parts. Just as soon as the knife-edges of the members 13 and 24 do pass, as previously stated, the member 13 is thrown to its open position as illustrated in Fig. 5, and the pawl and armature have completed their downward movement. Upon the return of the armature and its connected parts, the reverse action takes place between the members 13 and 24. During the greater portion of this upward movement, the upper inclined face of the cam 33 engages the adjacent end of the member 13 and maintains it in engagement with the stop 23. This continues until the knife-edges again pass each other, at which time the lower inclined face of the cam 33 comes into action and positively and quickly forces the member 13 downward, thereby closing the contacts 14-16. The point at which the knife-edges are just about to pass each other in this return movement is illustrated in Fig. 6.

In the form of the invention illustrated in Figs. 7 to 10 inclusive, the parts are practically the same as those before described except that the contact member 13 is replaced by contact springs 58-59-60, and contact member 24 is replaced by a similar member 61 which is provided with a somewhat different engaging face. The circuit through the winding of the interrupter is made and broken by the engagement and separation of the contact springs 59 and 60. Spring 59 is secured to, and movable with, spring 58, being spaced therefrom and connected therewith by means of an oscillating spacer 62. The stop 63 is also provided for engagement with the springs 59-60. The nose of the member 61 is adapted to engage the outer end of the spring 60 which is prolonged somewhat beyond the springs 58 and 59 and is provided with a suitable oscillating piece 64, against which the member 61 strikes. The member 61 is provided with two oppositely inclined faces 65-66 and with an intervening recessed portion 67. The notch or recessed portion 67 co-operates with the spring 58, and a pin 68 secured to the plate 11 co-operates with the inclined face 65. In the operation of this form of the invention, the parts normally occupy the position illustrated in Fig. 7. Upon the downward movement of the armature and the member 61, the inclined face 66 engages the spring 58 and thereby maintains the spring 59 in firm engagement with the stop 63 until said inclined

face slips by said spring. As soon as this takes place, the nose of the member 61 engages the insulating block 64 on spring 60 and forces the latter out of engagement with spring 59. This operation is illustrated clearly in Figs. 8 and 9. As soon as the inclined face 66 slips by spring 58, the lower shoulder formed by the recess 67 engages the under side of the spring 58, due to the action of the spring 28 upon the member 61. As before, the separation of the springs 59 and 60 does not take place until the armature and the pawl 34 practically reach the end of their forward movement. Upon the return movement of the armature and its connected parts, the spring 58, together with spring 59, is drawn upward. Until the spring 60 engages the stop 63, springs 59 and 60 cannot come into engagement because of the length of the inclined face as clearly illustrated in Fig. 9. Upon the further return movement of the armature and member 61, the spring 58, together with spring 59, is still further deflected, thus still maintaining the contact springs 59 and 60 separate. This separation continues until the pin 68, by engagement with the inclined face 65, forces the member 61 out of engagement with the spring 58. This, as before, takes place when the armature and the pawl 34 have practically reached the end of their return movement. As soon as the spring 58 is freed from the member 61, its resiliency is sufficient to return it and the spring 59 to normal position, thereby again establishing connection between contact springs 59 and 60.

From the above description, it will be seen that I have provided an interrupting device which maintains the circuit condition both upon the attraction and retraction of the armature until practically the end of the stroke of the armature is reached. It will also be observed that I have provided a device in which the parts are readily accessible and in which said parts are substantial and durable in construction while at the same time being comparatively economical to manufacture.

Obviously many alterations and modifications may be made in the construction of the interrupter herein disclosed without departing from the spirit and scope of my invention, and obviously too it is capable of use in many other relations than those of the automatic switch mechanism hereinbefore referred to. In view of this, I therefore do not wish to be limited to the specific matter disclosed, nor to the particular use specified, but aim to cover by the terms of the appended claims all reasonable alterations, modifications and varied applications of the invention.

What I claim as new and desire to secure by Letters Patent of the United States is:

1. An interrupter comprising a movable contact member, an actuating member hav-

ing a primary movement in the same general direction as said contact member and a secondary movement transverse thereto, and means including coöperating engaging parts 5 on said actuating and contact members whereby said contact member is moved when said actuating member reaches a definite point in its primary movement.

2. An interrupter comprising a movable contact member, means for limiting the stroke of said member, an actuating member having a primary movement in the same general direction as said contact member and a secondary movement transverse thereto, 10 means for limiting the primary movement of said actuating member, means for yieldingly pressing said actuating member toward said contact member, and means including coöperating engaging parts on said actuating and contact members whereby the said contact member is moved when said actuating member reaches a definite point in its primary movement.

3. An interrupter comprising an electromagnet, an armature therefor, a movable contact member having a movement in the same general direction as said armature, an actuating member for said contact member moved by said armature in a primary direction, 15 and independently of said armature in a direction transverse thereto and means including coöperating engaging parts on said actuating and contact members whereby said contact member is moved when said actuating member reaches a definite point in its primary movement.

4. An interrupter comprising an electromagnet, an armature therefor, a movable contact member having a movement in the same general direction as said armature, an actuating member for said contact member moved by said armature in a primary direction, 20 and independently of said armature in a direction transverse thereto, means for yieldingly pressing said actuating member in its secondary direction of movement toward said contact member, and means including coöperating engaging parts on said actuating and contact members whereby said contact member is moved when said actuating member reaches a definite point in its primary movement.

5. An interrupting device comprising an electromagnet, an armature therefor, a movable contact member having a movement in the same general direction as said armature, an actuating member for said contact member moved by said armature in a primary direction, 25 and independently of said armature in a direction transverse thereto, and means including coöperating engaging parts on said actuating and contact members whereby said contact member is moved when said armature practically reaches the end of its stroke.

6. An interrupting device comprising an electromagnet, an armature therefor, a movable contact member having a movement in the same general direction as said armature, an actuating member for said contact member moved by said armature in a primary direction, 30 and independently of said armature in a direction transverse thereto, means for yieldingly pressing said actuating member in its secondary direction of movement toward said contact member, and means including coöperating engaging parts on said actuating and contact members whereby said contact member is moved when said armature practically reaches the end of its stroke.

7. An interrupter comprising an oscillating contact member, a coöperating contact, an actuating member having a to-and-fro primary movement in the same general direction as said contact member and a secondary movement transverse thereto, and means including coöperating engaging parts on said actuating and contact members whereby said contact member breaks contact when said actuating member reaches practically the end of its forward stroke and makes contact when said member reaches practically the end of its return stroke.

8. An interrupter comprising an oscillating contact member, a coöperating contact, means for limiting the movement of said member, an actuating member having a to-and-fro primary movement in the same general direction as said contact member and a secondary movement transverse thereto, 45 means for limiting the primary movement of said actuating member, means for yieldingly pressing said actuating member toward said contact member, and means including coöperating engaging parts on said actuating and contact members whereby the contact member breaks contact when said actuating member reaches practically the end of its forward stroke and makes contact when said member reaches practically the end of its return stroke.

9. An interrupter comprising an electromagnet, an armature therefor, an oscillating contact member having a movement in the same general direction as said armature, a coöperating contact, an actuating member for said contact member moved to and fro by said armature in a primary direction and independently of said armature in a direction transverse thereto, and means including coöperating engaging parts on said actuating and contact members whereby said contact member breaks contact when said actuating member reaches practically the end of its forward stroke and makes contact when said member reaches practically the end of its return stroke.

10. An interrupter comprising an electromagnet, an armature therefor, an oscillating contact member having a movement in the

- same general direction as said armature, a coöperating contact, an actuating member for said contact member moved to and fro by said armature in a primary direction and independently of said armature in a direction transverse thereto, means for yieldingly pressing said actuating member in its secondary direction of movement toward said contact member, and means including 65
 10 coöperating engaging parts on said actuating and contact members whereby said contact member breaks contact when said actuating member reaches practically the end of its forward stroke and makes contact when said
 15 member reaches practically the end of its return stroke.
11. An interrupting device comprising an electromagnet, an armature therefor, an oscillating contact member having a movement in the same general direction as said armature, a coöperating contact, an actuating member for said contact member moved to and fro by said armature in a primary direction and independently of said armature 70
 20 in a direction transverse thereto, and means including coöperating engaging parts on said actuating and contact members whereby said contact member breaks contact when said actuating member reaches practically the end of its forward stroke and makes contact when said member reaches practically the end of its return stroke.
12. An interrupting device comprising an electromagnet, an armature therefor, an oscillating contact member having a movement in the same general direction as said armature, a coöperating contact, an actuating member for said contact member moved to and fro by said armature in a primary direction and independently of said armature 75
 35 in a direction transverse thereto, means for yieldingly pressing said actuating member in its secondary direction of movement toward said contact member, and means including coöperating engaging parts on said actuating and contact members whereby said contact member breaks contact when said actuating member reaches practically the end of its forward stroke and makes contact when said member reaches practically the end of its return stroke.
13. An interrupter having an oscillating contact member and an actuating member movable over the end of said contact member and yieldingly pressed into engagement therewith and having a cam surface for engaging said member so shaped as to force said contact member to its alternate position with a snap movement upon the operation 80
 40 of said actuating member.
14. An interrupter having an oscillating contact member and an actuating member movable over the end of said contact member and yieldingly pressed into engagement 85
 45 therewith and having a cam surface for engaging said contact member so shaped as to positively hold said contact member in one of its limiting positions during the movement of said actuating member until a definite point is reached and then to positively move said contact member to its alternate position with a snap movement.
15. An interrupter comprising an electromagnet, an armature therefor, an oscillating contact member and an actuating member moved by said armature over the end of said contact member and yieldingly pressed into engagement therewith and having a cam surface for engaging said contact member so shaped as to force said contact member to its alternate position when said armature practically reaches the end of its stroke.
16. An interrupter comprising an electromagnet, an armature therefor, an oscillating contact member and an actuating member moved by said armature over the end of said contact member and yieldingly pressed into engagement therewith and having a cam surface for engaging said contact member so shaped as to positively hold said contact member in one of its limiting positions until said armature practically reaches the end of its stroke and then to positively move said contact member to its alternate position with a snap movement.
17. An interrupter comprising a movable contact member, an actuating member having a movement in a direction transverse to that of said contact member, and means whereby said contact member is moved when said actuating member reaches a definite point in its movement.
18. An interrupter comprising an electromagnet, a supporting plate located at one end of said magnet and extending transversely of its axis and relatively movable contacts, and actuating connections between the armature and contacts, all mounted so as to lie in close proximity to said plate.
19. An interrupting device comprising an electromagnet, a supporting plate located at one end of said magnet and extending transversely of its axis, a movable contact member lying close to said plate and movable in a plane parallel thereto, a coöperating contact carried by said plate, an armature, a projection of said armature lying close to and movable in a plane parallel to said plate, and an actuating member extending from said projection into operative relation with said contact member.

In witness whereof, I hereunto subscribe my name this 31st day of December, 1906.

WILLIAM KAISLING.
